(57) **CLAIM**

The ornamental design for a temperature adjustment valve as shown and described.

DESCRIPTION

FIG. 1 is a first perspective view of a temperature adjustment valve showing my new design;

FIG. 2 is a second perspective view thereof;

FIG. 3 is a third perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a cross-section view taken along line **10-10** in FIG. 4; and,

FIG. 11 is a perspective view thereof, shown in use state. The evenly spaced broken lines in the drawings represent portions of the temperature adjustment valve that form no part thereof. The broken lines on top of the temperature adjustment valve in FIG. 11 illustrate the environment and do not form a part of the claimed design.
